UNITED STATES PATENT OFFICE.

CURT YORK, OF MEMPHIS, TENNESSEE.

IMPLEMENT FOR MAKING CHAIN LINKS.

Application filed April 27, 1921. Serial No. 464,890.

To all whom it may concern:

Be it known that I, CURT YORK, a citizen of the United States, residing at Memphis, in the county of Shelby and State of Tennessee, have invented certain new and useful Improvements in Implements for Making Chain Links, of which the following is a specification.

My said invention relates to an implement adapted to be used in the manufacture of chain links for making chains which are adapted for use in various relations but are particularly intended for use in making armor for automobile tires out of used tires. It is an object of my invention to provide a simple and effective implement which shall form a complete chain link in a single operation.

A further object of the invention is to provide means in connection with the link bending device to act as a gage for determining the length of the wire to be used in making a link.

Referring to the accompanying drawings which are made a part hereof and on which similar reference characters indicate similar parts,

Figure 1 is a plan view of the implement in position to begin the operation of forming a link.

Figure 2 is a similar view showing the position assumed by the parts in making the first bend in the wire,

Figure 3 is a section on line 3—3 of Figure 2, and

Figure 4 shows the completed link.

In the drawings reference character 5 indicates the base of the implement which may be attached to any convenient support by any conventional means such as screws 6. Upon base 5 are a pair of vertical pivots 7 each of which carries a lever 8 adapted to oscillate in a horizontal plane if the base be assumed to be fixed in a horizontal position. It will be evident that the position of the base may be varied without untoward results. For example, it may be attached to a vertical wall if desired. Each of the levers 8 has a recess 9 near the pivot and an inclined projection 10. A boss 11 extending upwardly from the base is adapted to bear against the ends of levers 8 and thus limit their outward movement.

In front of boss 11 is a bending member

12 about which the first bending operation takes place. This member has a laterally enlarged portion 13 adjacent the boss 11 and of similar altitude forming a stop to limit the movement of a vertically swingable lever 14 which when in contact with the stop assumes the position indicated in dotted lines in Figure 3. In rear of the stop 13 the former 12 has a vertically extending fin 15 in which is formed a slot 16 for the pin 17 which acts as a pivot for the lever 14. This lever is formed at its end to rest against the base 5 and has a lip 18 extending beneath the base and adapted to rest against a support such as indicated at 19. The fin has also a slot 10' to receive the inclined lugs 10 on levers 8.

In the operation of the device a wire of suitable weight is cut into lengths such as shown at 20 in Figure 1. The base 5 may be used as a gage in this connection, its longest dimension being the same as the length of wire necessary to form a link such as I have found most desirable in practice. This wire is placed between parts 11 and 13 and under the lugs 10 on levers 8 in the position shown in Figure 1. Then the arms are moved forward in the direction of the arrows to the position shown in Figure 2, the wire being bent as indicated, and the lugs 10 entering slot 10' if the thickness of the wire permits. The lever 14 is then moved in the direction of the arrow (Figure 3) to the dotted line position. The lever has a sliding fulcrum in slot 16, and so at first moves pivotally until the body of the lever 90 at the end of the crotch bears against the edge of the fin, after which the lever slides on the fin and continues to swing on its fulcrum until it reaches the dotted line position, bending the ends 21 of the wire as shown in Figure 4. The levers 8 are held by hand in the position shown in Figure 2, if necessary. The structure shown is intended to render this practically unnecessary as the form of the parts and the friction between them will tend to hold them in the position of Figure 2. The lugs 10 slope toward the front of the implement so as to hold the ends of the wire close to the fin 15 during the bending operation and the arm 14 thus acts 105 through the wire and the lugs 10 to assist in holding the arms 8 in position. In addition to this the lugs 10 by their engagement

under the upper face of the slot 10' hold the levers 8, 8 down and prevent lever 14 from exerting a bending action on their pivots 7, 7. When the movement of lever 14 5 to the dotted line position in Figure 3 has been completed a link is finished as shown in Figure 4. In the operation of the lever 14 the wire rests on its upper flat face and the pin and slot connection at 16, 17 permits 10 an easy rolling movement of the lever by which it comes to rest with its normally upper face on the flat faces of the closed levers 8, 8, which act as anvils to receive the blow of lever 14, and the ends of the wire are 15 bent over the lugs 10 so as to leave them in proper relation for joining with other links. In use for making such tire armor as described the sides of the link slip on the neck just above the bead of a piece cut crosswise 20 from a tire shoe, and the hooked parts engage the loop of the next link. A similar chain is formed at each side of the armor and in this manner a very effective armor may be made from old tires at little expense.

A succession of links may then be strung together as will be evident and in carrying out my particular purpose a tire of ordinary form will be cut into lengths to fit loosely 30 within the links and will be inserted into the chain as formed with each bead of the tire section at the under side of a link of one of the two chains which, together with the segments of the tire form an armor such 35 as may be placed about a pneumatic tire in use on an automobile or other vehicle.

It is to be understood the terms "horizontal" and "vertical" are used in the claims to indicate movement in the plane of the base 40 and in a plane at right angles thereto respectively. As hereinbefore explained the position of the base and attached parts is immaterial and these terms are used merely for description and not for limitation.

45 Having thus fully described my said invention, what I claim as new and desire to secure by Letters Patent, is:

1. An implement for forming chain links comprising a base, a pair of levers mounted 50 thereon for horizontal movement, a boss between the ends of said levers to limit their rearward movement, a former on the base having a head and a fin, said fin having an arcuate, substantially vertical slot, a third 55 lever having a pin in the slot and horizontally extending lugs on the first levers about which the third lever may form a second bend in the link after the same has been bent about the head by the first pair, substantially 60 as set forth.

2. A wire bending implement comprising 65 a base, a former on the base having a laterally enlarged head and a vertically extending fin, a horizontal slot in the fin, a pair of horizontally movable arms on the base

and projections on the arm adapted to hold down a wire being bent about the head and also adapted to enter said horizontal slot, substantially as set forth.

3. A chain making implement comprising 70 a base, a fixed former thereon, a pair of arms mounted for horizontal movement on the base to bend a wire about the former, an arm pivoted to the former having its upper face adjacent the base normally in the plane of 75 the base and adapted to contact with the ends of a wire lying on the base and to impart a second bend to the wire after the same has been bent by the first pair of arms, substantially as set forth.

4. An implement for forming chain links comprising a base having a flat face, a boss rising therefrom, a former spaced from the boss to admit a length of straight wire between them, a pair of levers pivoted on opposite sides of the boss and limited thereby as to their movement in one direction said levers having projections extending over the wire and being adapted to move the ends of the wire along said face and bend them 90 about the former, substantially as set forth.

5. An implement for forming chain links comprising a base having a flat face, a boss rising therefrom, a former spaced from the boss to admit a length of straight wire between them, a pair of levers pivoted at opposite sides of the boss and located at one side of said wire and adapted to move the ends of the wire along said face and bend the wire about the former, said former having a laterally expanded head and said levers having recesses cooperating therewith in bending the wire, substantially as set forth.

6. An implement for forming chain links comprising a base having a flat face, a boss 105 rising therefrom, a former spaced from the boss to admit a length of straight wire between them, said former having flat sides, a lever pivoted to the former, a pair of levers pivoted at opposite sides of the boss and located at one side of said wire and adapted 110 to move the ends of the wire along said face and bend the wire about the former, means adjacent said ends to hold the wire down at both sides of the former, said ends extending over a part of said first lever, and said lever adapted to move said ends along the sides of the former to bend them a second time, substantially as set forth.

7. An implement forming chain links comprising a base having a flat face, a boss rising therefrom, a former spaced from the boss to admit a length of straight wire between them, said former having flat faces, a lever pivoted to the former, a pair of levers 125 pivoted at opposite sides of the boss and located at one side of said wire and adapted to move the ends of the wire along said face and bend them about the former, forwardly inclined projections on the levers of 130

said pair to hold down the wire adjacent its ends, said ends extending over a part of said first lever, and said lever adapted to move said ends along the faces of the former to 5 bend them a second time, substantially as set forth.

In witness whereof, I have hereunto set

my hand and seal at Memphis, Tennessee this 25th day of April, A. D. nineteen hundred and twenty-one.
